JOHN C. HOADLEY, OF LAWRENCE, MASSACHUSETTS.

Letters Patent No. 105,078, dated July 5, 1870.

IMPROVEMENT IN STEAM-ENGINES

The Schedule referred to in these Letters Patent and making part of the same.

To all whom it may concern:

Be it known that I, JOHN C. HOADLEY, of Lawrence, in the county of Essex and State of Massachusetts, have invented Improvements in the Details of Arrangement and Construction of Steam-Engines; and I do hereby declare that the following, taken in connection with the drawing which accompanies and forms part of this specification, is a description of my invention sufficient to enable those skilled in the art to practice it.

The invention to be herein described is designed, in most of its parts, for application to portable engines, that is, engines in which all the parts are connected, so that they are all moved as a unit, the boiler serving as the bed for the cylinder and the shaft-bearings, either with or without a bed-plate.

One part of my invention consists in so constructing and locating the cylinder that the volatile products of combustion which are carried out of the chimney by the exhaust-blast pipe are made to pass around and in contact with the cylinder, to keep it at or about the temperature of the steam.

Another part of my invention consists in locating the feed-water heater in the smoke-box, between the ends of the boiler-flues and the passage where the volatile products of combustion pass around the cylinder, so that, in heating the feed-water, enough heat shall be abstracted by the feed-water from the escaping smoke and gases to prevent overheating the cylinder thereby.

Figure 1 of the drawing represents, in vertical longitudinal section, a portable steam-engine, embodying my invention.

Figure 2 represents a front, and

Figure 3, a rear end view of the same.

Figure 4 shows, in vertical sectional elevation, my peculiar combination of the safety-valve and steam-whistle.

The boiler is of the common multitubular locomotive type, and therefore needs no description.

The cylinder is located over the smoke-box of the boiler, and is so cast that the smoke from the smoke-box moves through passages made in the casting around the cylinder to a nozzle, *a*, on which the chimney is fitted.

A regulator of any suitable kind, working any suitable governor-valve, is located above, and is attached to the steam-drum of the boiler, the regulator-valve spindle passing through a suitable stuffing-box.

The regulator-valve and its case *b* are located near the top of the interior of the steam-drum, so as to take into the steam-pipe *c d* steam which has the least quantity of water mechanically held therein of any in the boiler.

The steam passes down through pipe *c* past the

throttle or steam-valve *e*, (the rod of which passes through a suitable stuffing-box to a lever located at the fire-box end of the boiler,) into and through pipe *d*, to the "ox-horn" pipe *f* in the smoke-box, which pipe *f* is connected with and discharges into the valve-chest of the cylinder.

The exhaust steam passes from the cylinder, in the usual manner, to the blast-pipe, as seen at *g*.

The feed-water heater is made of pipes *g*, arranged in a tortuous manner in the smoke-box, above the outlet of the smoke-flues, one end of the feed-pipe entering the boiler at any suitable place, and the other end being connected to the feed-pump, not shown, which may be worked as usual from the cross-head, or by an eccentric on the main shaft.

The heater *g* intercepts the outgoing current of smoke and gases between the flues and the entrance to the passage leading to the chimney around the cylinder, and absorbs considerable of the heat from the escaping volatile products of combustion.

On one side of the boiler, and near the furnace end, is a pipe, *h*, which has two branches, *i j*, the branch *i* being connected with the steam-space of the boiler, and the branch *j* entering the boiler below the lowest water-level.

To this pipe, which is fully in view of the fireman and engine-tender when at work in attending the fire, are attached the gauge-cocks *k*, the glass water-gauge *l*, and the pressure-indicating gauge *m*.

The pressure-gauge is connected by pipe *n* with the steam in the steam-drum, and by pipe *o* with the steam in pipe *c d*, by means of a three-way cock at *p*, so that, by turning said cock, the steam pressure on the boiler can be read upon the gauge, or the lessened pressure of steam in pipe *c d* showing how much the steam is reduced in pressure by "throttling" through the regulator-valve.

In the upper part of pipe *h* is a valve-seat, *q*, on which rests the safety-valve *r*, which is of the poppet variety, guided by wings fitting the steam-passage to the valve-seat.

The valve *r* is deeply concaved from its upper side, and is held to its seat against steam pressure by a follower, *s*, which is acted on by spring *t*, which spring is made more or less tense by adjusting, down or up, the screw-cap *u*, which cap serves also to support the whistle-bell *v*, the upper part of the cap being made like the base of an ordinary steam-whistle.

To lift the valve *r* to blow the whistle there is coupled to follower *s* a spindle, *w*, which can be raised by lever *x*, which lever cannot be used to hold the safety-valve down upon its seat, as the spindle has a long slot in it, against the upper boundary of which only is the lever *x* operative.

The lower end of spindle *w* is screw-threaded, and

connects with a nut, *y*, coupled to the follower *s*. As the threads on the spindle *w* have the same pitch with the threads on the screw-cap *u*, the valve *r* is not affected when the tension of spring *t* is adjusted by turning the screw-cap *u* up or down.

The follower *s* is kept from turning, when the rod *w* is turned in adjusting the pressure of the spring *t*, by means of ears, *z z*, sliding freely in vertical channels, *a a'*, in the sides of the case *h*.

A pipe, not shown, is extended from the orifice *i* up to the interior of the drum, near the top, to conduct dry steam to the whistle through the safety-valve; and a baffle, not shown, is put into the pipe *h*, below the safety-valve, to prevent the passage of water to the safety-valve and whistle, in blowing off steam, by excess of pressure, and in blowing the whistle.

I claim—

A steam-engine, having its cylinder so constructed and located that the hot volatile products of combustion

will pass in direct contact with the cylinder casting around and partially jacketing it, in moving from the flue-ends to the chimney-outlet.

Also, the arrangement of pipes, for heating the feed-water, within the smoke-box, between the flue-outlets and the smoke-jacket of the cylinder, substantially as described.

Also, a steam-gauge, so connected by pipes *n* and *o*, and means for controlling the flow of steam through said pipes, with the steam in the boiler, and with the steam in the pipe between the automatic regulator-valve and the steam-cylinder, that, with the single gauge, can be tested, at will, the pressure of the steam in either space.

J. C. HOADLEY.
